(57) **CLAIM**

The ornamental design for a JAW FOR A SURGICAL INSTRUMENT, as shown and described.

DESCRIPTION

FIG. 1 is a perspective view of a jaw for a surgical instrument in accordance with the new design;

FIG. 2 is a front view of the jaw of FIG. 1;

FIG. 3 is a rear view of the jaw of FIG. 1;

FIG. 4 is a right side view of the jaw of FIG. 1;

FIG. 5 is a left side view of the jaw of FIG. 1;

FIG. 6 is a top plan view of the jaw of FIG. 1; and

FIG. 7 is a bottom plan view of the jaw of FIG. 1.

The broken lines in the figures are directed to portions of the jaw for a surgical instrument that form no part of the claim.

1 Claim, 6 Drawing Sheets
